UNITED STATES PATENT OFFICE.

UNITO PISI, OF PHILADELPHIA, PENNSYLVANIA.

STEAM BOILER.

Application filed May 6, 1926. Serial No. 107,250.

This invention relates to boilers such as are employed for the generation of steam and has special reference to a boiler of the horizontal tubular type particularly adapted 5 for use as a stationary or marine boiler.

One important object of the invention is to provide an improved general construction of boilers of this type.

A second important object of the invention 10 is to provide an improved arrangement of water and fire tubes in a boiler of this class.

A third important object of the invention 15 is to provide an improved form of boiler having an improved arrangement of water heating pipes certain of which are arranged in a novel manner to secure preheating of the feed water before it reaches the steam making part of the boiler.

20 A fourth important object of the invention is the provision of a novel and compact arrangement of superheater tubes in such a boiler.

With the above and other objects in view 25 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the boiler 30 with one side of the housing removed to disclose the interior arrangements.

Figure 2 is a similar view from the top of the boiler.

Figure 3 is a front elevation similar to 40 Figure 1, certain parts being broken away to show those behind.

Figure 4 is an enlarged view of a portion of the boiler as shown in Figure 3.

Figure 5 is an enlarged longitudinal section 45 through a portion of the boiler showing the fire, water and superheater tube arrangement in the steam generating part of the boiler.

Figure 6 is a view showing a part of the 50 feed water heater in side elevation.

Figure 7 is a view taken transversely of the boiler showing the arrangement of the feed water headers.

Figure 8 is a partial end view of one of 55 the steam drums and its water leg.

Figure 9 is a side elevation of the parts shown in Figure 8.

Figure 10 is a side view, partly in section of a hollow plug used herewith.

Figure 11 is an enlarged section on the 60 line 11—11 of Figure 1.

Figure 12 is a section on the line 12—12 of Figure 11.

In the construction of this boiler the feed 65 water pipe 10 leads in from the back of the boiler near the top thereof and after passing through the boiler housing extends transversely of the housing in a lower or cold feed water header 11 which is closed at the end remote from the pipe 10. Above and parallel to this header is an upper or hot feed water header closed at both ends having a front branch 12 and a rear branch 13. Connecting these feed water headers is a series 70 of banks of feed water pipes 14 each of 75 substantially U-shape and extending from the lower header well towards the front of the boiler and then bent upwardly and backwardly and connected to the upper header 80 branch 12. These banks are of different 85 lengths as shown.

The boiler has the usual front and back plates 15 and spaced within these plates are the main water headers 16. Each of these main headers is preferably made in three 85 sections and from the top of each section extends a water leg 17. There are thus three pairs of these water legs, each pair consisting of a front water leg and a corresponding rear water leg. Each pair of these water 90 legs supports a steam drum 18 which thus runs longitudinally of the boiler at its top. The rear water legs lie between the front and rear branches 12 and 13 of the upper feed water header and the rear branch 13 95 is connected to the rear water legs by nipples 19.

The circulation so far is from the feed water pipe 10 into the lower header 11, through the heater pipes 14 to the branch 12, then to 100 the branch 13 and from there through the nipples 19 to the rear water legs 17 to the rear main water header 16. These main water headers are connected by water tubes 20 and within each tube 20 is a concentric fire tube 21, the ends of which pass clear through the main water headers and open into the spaces between these headers and the end walls of the boiler.

On the top of each steam drum 18 is mount- 110

ed a steam valve 22 and across the tops of the drums extends a steam header 23 from the ends of which extend downwardly and rearwardly the steam legs 24 which have their lower ends connected by a lower steam header 25. Through the lowermost row of fire tubes extends a series of superheater tubes 26 concentrically spaced from the inner walls of said fire tubes and similar superheater tubes 27 run through all the remaining fire tubes except the uppermost row. Each vertical row of superheater tubes is connected in pairs, staggered front and rear, by short superheater headers 28. The uppermost row of these superheater tubes is connected to a main steam pipe 29 by which the steam is conducted to any suitable place of use such as a steam turbine or other steam engine.

Following the circulation from the rear water legs it will be seen that the water flows down in the rear main water header through the pipes 20 to the front main water header. In these pipes and headers the water is heated by the flame and hot gases from the grate 30 which not only pass up around the outside of the water tubes but through the fire tubes so the thin layer of water around the fire tubes is heated with great efficiency and boils rapidly and passes up the front water legs 17, the tubes being inclined for this purpose, and into the steam drums. From there the steam passes through the steam header and legs and back and forth in an upward direction through the superheater tubes to the main steam pipe 29.

A fire arch 31 is preferably positioned below the rear branch 13 to keep the flame and hot gases from impinging directly on the feed water header branches 13 and 12.

Thus, with this boiler steam is produced rapidly and efficiently and the feed water is heated and the steam superheated.

In cases where it is difficult to insert or bead certain of the tubes for the assembling of the device, as for instance in the feed water headers and other parts I drill holes in the headers opposite the tube end so that a tube expanding tool can be passed through the header and into the tube end. These holes are afterwards plugged with a hollow plug 32, with a closed inner end, the plug expanded after insertion by a tube expanding tool.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a boiler, a series of water tubes, a series of fire tubes each extending longitudinally through a respective water tube, and a

series of superheater tubes each extending longitudinally through a respective fire tube.

2. In a boiler, a series of water tubes, a series of fire tubes each extending longitudinally through a respective water tube, a series of superheater tubes each extending longitudinally through a respective fire tube, headers common to all of the water tubes at each end thereof, and other headers connecting the superheater tubes in sets, the last mentioned headers connecting the superheater tubes of each set in successive order.

3. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, and superheater tubes connected in series and each passing longitudinally through a respective fire tube.

4. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, and means to convey steam from the steam drum to the lowermost ends of the series of superheater tubes.

5. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, means to convey steam from the steam drum to the lowermost ends of the series of superheater tubes, and means to supply water to one of said water legs including feed water heating elements between the tubes and said drum.

6. In a boiler, a pair of spaced water headers each having a front and a back wall, water tubes secured to the proximal walls of said headers and affording communication between said headers, fire tubes each extending through said headers to open at their remote walls and each passing longitudinally

through a respective water tube, superheater tubes connected in series and each passing longitudinally through a respective fire tube, water legs projecting upwardly from the tops 5 of the water headers, a steam drum carried by said water legs and communicating therewith, a steam header extending across the top of said steam drum and having valved communication therewith, steam legs extending 10 downwardly and rearwardly from the ends of the steam header, and a second steam header extending transversely across the lower part of one of the water headers and having the lower ends of the series of superheater tubes 15 connected thereto.

7. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, a steam header extending across the top of said steam drum and having valved communication therewith, steam legs extending downwardly and rearwardly from the ends of the steam header, a second steam header extending transversely across the lower part of one of the water headers and having the lower ends of the series of superheater tubes connected thereto, and means to supply water to one of said water legs including feed water heating elements between the tubes and said drum.

45 8. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, means to convey steam from the steam drum to the lowermost ends of the series of superheater tubes, a cold feed water header extending transversely of the boiler adjacent one end thereof and above said tubes, said feed water header being closed at one end and communicating with a feed water pipe at its other end, a hot feed water header having two communicating branches, one of which lies above the cold feed water header parallel thereto and the other of which lies on the opposite side of one of said

water legs, **U**-shaped pipes each having its ends connected respectively to the cold feed water header and the first mentioned branch of the second feed water header, said second header being closed at both ends, and nipples connecting said second branch with the adjacent water leg. 70

9. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, means to convey steam from the steam drum to the lowermost ends of the series of superheater tubes, a cold feed water header extending transversely of the boiler adjacent one end thereof and above said tubes, said feed water header being closed at one end and communicating with a feed water pipe at its other end, a hot feed water header having two communicating branches one of which lies above the cold feed water header parallel thereto and the other of which lies on the opposite side of one of said water legs, U-shaped pipes each having its ends connected respectively to the cold feed water header and the first mentioned branch of the second feed water headers, said second header being closed at both ends, nipples connecting said second branch with the adjacent water leg, a steam header extending across the top of said steam drum and having valved communication therewith, steam legs extending downwardly and rearwardly from the ends of the steam header, and a second steam header extending transversely across the lower part of one of the water headers and having the lower ends of the series of superheater tubes connected thereto. 10. In a boiler, a pair of spaced water headers each having a front and a back wall, water tubes secured to the proximal walls of said headers and affording communication between said headers, fire tubes each extending through said headers to open at their remote walls and each passing longitudinally through a respective water tube, superheater tubes connected in series and each passing longitudinally through a respective fire tube, water legs projecting upwardly from the tops of the water headers, a steam drum carried by said water legs and communicating therewith, means to convey steam from the steam drum to the lowermost ends of the series of superheater tubes, a cold feed water header extending transversely of the boiler adjacent one end thereof and above said tubes, said feed water header being closed at one end and communicating with a feed water pipe at its other end, a hot feed water header having two communicating branches one of which lies above the cold feed water header parallel thereto and the other of which lies on the opposite side of one of said water legs, U-shaped pipes each having its ends connected respectively to the cold feed water header and the first mentioned branch of the second feed water headers, said second header being closed at both ends, nipples connecting said second branch with the adjacent water leg, a steam header extending across the top of said steam drum and having valved communication therewith, steam legs extending downwardly and rearwardly from the ends of the steam header, and a second steam header extending transversely across the lower part of one of the water headers and having the lower ends of the series of superheater tubes connected thereto.

tubes, said feed water header being closed at one end and communicating with a feed water pipe at its other end, a hot feed water header having two communicating branches 5 one of which lies above the cold feed water header parallel thereto and the other of which lies on the opposite side of one of said water legs, U-shaped pipes each having its ends connected respectively to the cold feed 10 water header and the first mentioned branch of the second feed water headers, said second header being closed at both ends, nipples connecting said second branch with the adjacent water leg, a steam header extending across

the top of said steam drum and having valved 15 communication therewith, steam legs extending downwardly and rearwardly from the ends of the steam header, a second steam header extending transversely across the lower part of one of the water headers and 20 having the lower ends of the series of superheater tubes connected thereto, and a main steam pipe to which all of the remaining ends of the series of superheater tubes is connected.

In testimony whereof I affix my signature.

UNITO PISI.
